Primary Examiner—Louis S. Zarfas*Assistant Examiner*—Monica A. Weingart*Attorney, Agent, or Firm*—Kenyon & Kenyon[57] CLAIM

The ornamental design for a make-up planner, as shown and described.

DESCRIPTION

FIG. 1 is a perspective view of a make-up planner with an insert showing my new design;

FIG. 2 is a front elevational view of an insert for the make-up planner of FIG. 1;

FIG. 3 is a right side elevational view of the insert of FIG. 2;

FIG. 4 is a left side elevational view of the insert of FIG. 2;

FIG. 5 is a rear elevational view of the insert of FIG. 2;

FIG. 6 is a top plan view of the insert of FIG. 2;

FIG. 7 is a perspective view of the make-up planner of FIG. 1 wherein the insert is removable;

FIG. 8 is a front elevational view of the removable insert of FIG. 7;

FIG. 9 is a right side elevational view of the insert of FIG. 7;

FIG. 10 is a left side elevational view of the insert of FIG. 7;

FIG. 11 is a rear elevational view of the insert of FIG. 7; and, FIG. 12 is a top plan view of the insert of FIG. 7.

The broken line showing of the planner holder in FIGS. 1 and 7, is for illustrative purposes only and forms no part of the claimed design.
